Patented May 3, 1921.

UNITED STATES PATENT OFFICE.

HARRY SILVERMAN, OF BROOKLYN, NEW YORK.

JEWEL-MOUNT.

1,376,974.

Specification of Letters Patent.

Patented May 3, 1921.

Application filed July 26, 1920. Serial No. 399,113.

To all whom it may concern:

Be it known that I, HARRY SILVERMAN, a citizen of the United States, and a resident of the borough of Brooklyn, county of Kings, city and State of New York, have invented certain new and useful Improvements in Jewel-Mounts, of which the following is a specification.

My invention relates to the mounting of precious stones, and imitations thereof, generally, and particularly to rings formed with what is known technically as the "basket" type of mount, which affords open space for the back of the jewel, so that it may be inspected from the rear.

As is well known in the art, only diamonds and other very hard stones can be successfully claw-mounted because the pressure on the jewel involved in such setting is apt to crack and injure the weaker stones,—so much so that inferior stones and imitation jewels cannot be safely claw set.

My improvements are designed to obviate this difficulty, and also to enable retail jewelers and others to set stones selected by purchasers without resort to specially skilled labor, which has heretofore been indispensable. In other words, I provide, as an article of manufacture for disposal to retail dispensers, the component parts of a ring adapted for jewel setting, which parts may be conveniently and expeditiously assembled and joined together in such manner as to effectually secure a jewel in position,—the invention consisting in the specific construction and arrangement of parts described and claimed, and distinctive features being the use of a jewel base or bed plate in conjunction with a face or cap plate substantially as hereinafter set forth.

In the accompanying drawings I show, upon an enlarged scale, a finger ring embodying the essential features of my invention, it being understood however that the ornamental design and configuration thereof may be varied and modified without departing from the spirit and intent of my invention, which relates more particularly to the method of, and means for, securing the jewel in position thereon.

Figure 1, is a face view of the ring, complete;

Fig. 2, is a side elevation thereof;

Fig. 3, is a section thereof taken on the plane of line 3—3, Fig. 1;

Fig. 4, is a side elevation of the ring without the jewel setting plates;

Fig. 5, is a face view of the ring as shown in Fig. 4;

Fig. 6, is a face view of the jewel cap plate; 60

Fig. 7, is a rear view thereof;

Fig. 8, is an edge view of said cap plate;

Fig. 9, is a cross section thereof taken on the plane of line 9—9, Fig. 7;

Fig. 10, is a front view of the jewel bed plate; 65

Fig. 11, is a rear view thereof;

Fig. 12, is an edge view of said jewel bed plate;

Fig. 13, is a transverse section thereof 70 taken on the plane of line 13—13, Figs. 10 and 11.

The sides of the main portion of the finger loop L, are of any ordinary or preferred shape in cross section, and the front portion 75 of the loop is formed with the hollow "basket" extension l, constituting the support for the jewel mount. The outer edge of the said hollow extension l, is in the form of a circumscribing rim l', of any configuration 80 desired, that shown in the drawings, and particularly in Fig. 5, thereof, being hexagonal, although it might of course be round, square, or of any contour required, in accordance with the shape and peripheral outline of the jewel mount to be fitted thereto.

This circumscribing rim l', is the seat upon and to which the jewel bed plate b, is secured, preferably by soldering, and said bed plate is preferably made with a rear 90 shoulder b', fitting within the rim l', as shown more particularly in Fig. 3, so as to centralize the bed plate and strengthen the connection between the contactual surfaces.

The bed plate b, is formed with a central 95 aperture b², on the edge of which the rear medial portion of the jewel j, is seated as illustrated in Fig. 3,—the shape of the aperture b², being adapted to that of the jewel to be mounted.

The jewel j, is held securely to its seat on the bed plate b, by means of the cap plate c, formed with a central aperture c', the edges of which overlap the edges of the jewel as shown in the aforesaid Fig. 3, of 105 the drawings,—so that a positive connection between the cap plate c, and the bed plate b, affords a permanent and reliable mount for the stone or other jewel thus positioned with its circumscribing edges interposed 110

between the inner edges of said mount plates *b*, *c*.

Obviously various mechanical expedients may be resorted to for the purpose of rigidly 5 securing the cap plate *c*, to the bed plate *b*, and hence I do not limit myself to the identical form and arrangement of parts shown for this purpose in the drawings, in which specific construction the bed plate *b*, is 10 formed with a plurality of peripheral clenched prongs *b**, which are bent over and down upon the cap plate *c*, which latter is formed with peripheral notches *c**, for the accommodation of the shanks of the said clenched 15 prongs.

Both the bed plate *b*, and the cap plate *c*, may be cheaply and accurately formed by means of dies, in a manner well known in the arts, in which case the face of the cap plate *c*, may be embossed with any desired or appropriate ornamentation, indicated symbolically by the lines *d*, *d*, in Figs. 1 20 and 6, thus imitating and affording the effect of the engraver's tool, and embellishing 25 the mount in a manner similar to that heretofore customary in the finishing of "basket" mounts.

A retail jeweler being furnished with and carrying in stock the loop *L*, bed plate *b*, and cap plate *c*, can with ordinary tools, and without the aid or exercise of specially skilled labor such as that heretofore essential for the purpose, expeditiously and successfully set any stone or jewel selected by 30 a customer without the delay, inconvenience and expense involved in sending the work to a professional stone setter. Furthermore the setting thus attained is much more positive and secure, and danger of injury to the 35 stone or jewel is obviated because the binding pressure is applied only to cap plate *c*, and not to the jewel, as is the case in claw or "bead" mounts.

For this latter reason also the cheaper and 40 more fragile stones, and imitation jewels, may be safely and securely mounted without danger of fracture or injury; and the retail jeweler, if possessed of only ordinary skill in the art, may become his own jewel 45 setter or mounter.

What I claim as my invention and desire to secure by Letters Patent is,

1. A ring of the character designated, comprising a finger loop formed with a hollow support for a jewel mount having a recess for supporting the jewel, and said jewel mount consisting of a jewel bed plate adapted to be soldered to said hollow support on the loop, and a jewel cap plate fitting over the jewel bed plate and adapted to be secured thereto by clenched prongs on the bed plate, for the purpose set forth.

2. A ring of the character designated, comprising a finger loop formed with a hollow support for a jewel mount having a re-

cess for supporting the jewel, and said jewel mount consisting of a jewel bed plate adapted to be soldered to said hollow support on the loop, and a jewel cap plate fitting over the jewel bed plate and adapted to be secured thereto by clenched prongs on the bed plate, the said jewel cap plate being formed with notches for the accommodation of the shanks of said clenched prongs on the jewel bed plate, for the purpose described. 75

3. A ring of the character designated, comprising a finger loop formed with a hollow support for a jewel mount having a recess for supporting the jewel, and said jewel mount consisting of a jewel bed plate adapted to be soldered to said hollow support on the loop, and a jewel cap plate fitting over the jewel bed plate and adapted to be secured thereto by clenched prongs on the bed plate, the back of said jewel bed plate being shouldered to fit within the said hollow mount support on the loop, for the purpose described. 80

4. A ring of the character designated, comprising a finger loop formed with a hollow support for a jewel mount having a recess for supporting the jewel, and said jewel mount consisting of a jewel bed plate adapted to be soldered to said hollow support on the loop, and a jewel cap plate fitting over the jewel bed plate and adapted to be secured thereto by clenched prongs on the bed plate, the face of said jewel cap plate being die-embossed, for the purpose set forth. 90

5. A ring of the character designated, comprising a finger loop formed with a hollow support for a jewel mount having a recess for supporting the jewel, and said jewel mount consisting of a jewel bed plate adapted to be soldered to said hollow support on the loop, and a jewel cap plate fitting over the jewel bed plate and adapted to be secured thereto by clenched prongs on the bed plate, the back of said jewel bed plate being shouldered to fit within the said hollow mount support on the loop, and the said jewel cap plate being formed with notches to accommodate the shanks of the said clenched prongs on the jewel bed plate, for the purpose described. 105 110 115

6. A ring of the character designated, comprising a finger loop formed with a hollow support for a jewel mount having a recess for supporting the jewel, and said jewel mount consisting of a jewel bed plate adapted to be soldered to said hollow support on the loop, and a jewel cap plate fitting over the jewel bed plate and adapted to be secured thereto by clenched prongs on the bed plate, the back of said jewel bed plate being shouldered to fit within the said hollow mount support on the loop, and the said jewel cap plate being formed with notches to accommodate the shanks of the said clenched prongs on the jewel bed plate, and 120 125 130

being also die-embossed, for the purpose set forth.

7. A ring of the character designated, comprising a finger loop formed with a hollow support for a jewel mount having a recess for supporting the jewel, and said jewel mount consisting of a jewel bed plate adapted to be soldered to said hollow support on the loop, and a jewel cap plate fitting over the jewel bed plate and secured thereto by positive means, for the purpose described.

8. A ring of the character designated, comprising a finger loop formed with a hol-

low support for a jewel mount having a recess for supporting the jewel, and said jewel 15 mount consisting of a jewel bed plate adapted to be soldered to said hollow support on the loop, and a jewel cap plate fitting over the jewel bed plate and positively secured thereto by clenching means, for the purpose 20 described.
